(57) **CLAIM**

The ornamental design for an infrared digital night vision display, as shown and described.

DESCRIPTION

FIG. 1 is a first perspective view of an infrared digital night vision display showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the infrared digital night vision display in which the design is embodied that form no part of the claimed design.
